C. F. GESCHICKTER

WINDOW SCREEN

Filed Oct. 19, 1923

Fig. 1

Patented May 5, 1925.

1,536,489

UNITED STATES PATENT OFFICE.

CHARLES F. GESCHICKTER, OF WASHINGTON, DISTRICT OF COLUMBIA.

WINDOW SCREEN.

Application filed October 19, 1923. Serial No. 669,592.

To all whom it may concern:

Be it known that I, CHARLES F. GE-
SCHICKTER, a citizen of the United States,
residing at Washington, in the District of
Columbia, have invented certain new and
useful Improvements in Window Screens,
of which the following is a specification.

One of the usual ways of securing the
window screens to the window frame is by
means of a tongue and groove construction,
but the objection to this is that when there
is a desire to wash the windows the screens
must be bodily removed, which in some in-
stances is difficult and inconvenient. Some
expedients are shown in the prior art of
providing side stiles of the screen with re-
cesses in which springs are placed whereby
the screen may be removed by pressing it
transversely to disengage one of the side
stiles from its slideway. These expedients
are more or less objectionable in view of the
necessarily restricted cross section of the side
stile, because any recesses in the side stile
weaken the structure. It is also old in the
prior art to hinge a screen.

The object of my invention is to provide
means whereby a window screen may be
free to slide on its guideways and at the
same time may be moved outward from the
window on hinges whereby the window will
be free from obstruction during the opera-
tion of washing.

The further object of my invention is to
provide a combined sliding and hinged
screen, and at the same time maintain the
maximum strength of the side stiles.

And with these and other objects in view
my invention consists of the parts and combi-
nation of parts as will hereinafter be more
fully set forth.

In the drawings:

Figure 1 is a front elevation of a window
provided with my improved screen.

Figure 2 is an enlarged sectional view of
the line 2—2, Figure 1, looking in the direc-
tion of the arrow.

Figure 3 is an enlarged detail sectional
view of the bead.

Figure 4 is an enlarged detail sectional
view through the hinge and its associated
parts.

The reference numeral 1 designates a win-
dow frame of any approved construction
having the window sash stop beads 2.

According to my invention I secure in a
suitable manner on the stop bead 2 a mem-

ber 3 having a groove 4 extending through-
out its length. I prefer to line this groove
4 with a thin sheet metal slideway 5 to the
top edges of which are crimped the laterally
extending arms 6 and 7. The arm 6 is pro-
vided with a downward extension 7' bearing
against one side wall of the member 3, while
the arm 7 is provided with a forwardly ex-
tending strip 8. The crimp joint between
the arms 6 and 7 and the slideway 5 con-
stitute an overhanging or undercut shoulder
9 at each side of the slideway whereby the
entrance to the slideway is in the nature of
a restricted throat.

10 is a side stile of the screen frame and
11 is the usual wire mesh used in wire
screens. My improved slide comprises the
arms 12 and 13 which are connected by a
semitube like protuberance 14 which is
adapted to slide in the slideway 5, said pro-
tuberance having grooves 15 in each side
thereof near the top which are adapted to
receive the shoulders 9, thus forming an in-
terlocking relation between the shoulders 9
and the slide. A hinge member 15' is se-
cured to the outer end of the arm 12 and in
turn is secured to the side stile 10 of the
screen by suitable screws, or the like, 16.
The arm 13 of the slide is provided with for-
wardly projecting member 17 constituting a
thumb piece whereby when the screen is
swung upon its hinge the slide protuberance
14, which is transversely flexible, may be
compressed sufficiently to press one edge of it
to such an extent that the groove 15 is moved
from an engagement with the shoulder 9
whereby the slide is free to be removed from
the slideway 5. It will be understood that
when the screen is in its normal operative
sliding position the thumb piece 17 cannot be
operated to cause disengagement between the
slide 14 and the slideway 5 so that the
screen may not be accidentally disengaged
from its slideway. On the opposite side of
the window I mount a bead 18 on the bead 2
and form a groove 20 in said bead 18
throughout its length into which a slide
member 21, secured to the side stile of the
screen, projects whereby the screen is guided
in its sliding movement.

At predetermined intervals in the length
of the bead 18 I cut one wall of the groove 20
away to form a notch 22 into which is se-
cured a box 23 carrying a coiled spring 24
and bolt 25. It will be noted that the hous-
ing 23 does not extend the full length of the

notch 22; however, the bolt 25 projects sufficiently below the bottom edge of the housing 23 to constitute an obstruction across that portion of the notch below the housing 5 whereby the slide element 21 cannot accidentally slip out through the notch. When it is desired to swing the screen on its hinge the screen is brought to its lower-most position, in which position the slide piece 21 is 10 opposite or back of the bolt 25. The bolt 25 gives under pressure of the piece 21, whereby the slide piece 21 is free to pass through the notch 22 when the screen is swung on its hinge. When the screen is 15 swung back into operation the bolt is operated in a similar manner.

By my improved construction it will be seen that I have provided a screen and slide base for the same whereby the screen may 20 be moved up and down in its slideways very readily, and when it is desired to wash the window the screen may be readily swung upon its hinge out of the way, and further when it is desired to remove the screens for 25 winter storage this may be done very easily and quickly.

The parts constituting my invention are of such construction that they are durable, cheap and simple to manufacture.

30 While I have selected the specific construction shown in the drawings to illustrate my invention, it will be understood that changes may be made in the details of construction within the scope of the appending 35 claims.

The lower end of the bolt 25 is cam-like; therefore by pressing the slide piece 21 against this cam-like end of the bolt the bolt 40 is automatically moved upward and out of the path of the slide piece 21 so that these slide pieces 21 are free to move upward and forward whenever it is necessary or desirable to swing the screen on its hinges.

What I claim is:

45 1. The combination with a window frame, of an undercut slideway secured to said frame, a resilient slide mounted in said runway, and a frame carried by and hingedly connected to said slideway.

50 2. The combination with a window frame, of an undercut slideway secured to said frame, a resilient slide mounted in said runway, an arm on said slide whereby the slide may be flexed to attach or detach it 55 to or from the slideway, and a frame hinged to said slideway, whereby said last named frame may move in unison with or relative to said slideway.

3. The combination with a window frame, 60 of an undercut slideway secured to said

frame, a resilient slide mounted in said slideway, a frame hinged at one side to said slide, and means connecting the other side of the last named frame to the other side of the window frame.

65

4. The combination with a window frame, of an undercut slideway secured to said frame, a resilient slide mounted in said slideway, a frame hinged at one side to said slide, a slideway on the other side of said window frame having transverse openings, means resiliently closing said openings and a slide secured to said other side of the second frame adapted to enter said slideway 70 through said transverse openings.

75

5. The combination with a window frame of an undercut slideway secured to said frame, a transversely resilient slide mounted in said slideway, and a frame hinged to said slide.

80

6. In a device of the character described, a slide for a screen or window sash, comprising an elongated open bend member transversely flexible, shoulders on said slide and a hinge member secured to one side of 85 said slide.

85

7. In a device of the character described, a slide for a screen or window sash, comprising an elongated member bent to semitubular form and flexible transversely, an arm extending laterally from and connected to each side of said semitubular form, a hinge connected to one of said arms, and a groove formed in said member on each side between the said semitubular form and 90 lateral arms.

90

8. In a device of the character described, an elongated slide having a protuberance on one side, a groove in each side of said protuberance, a hinge secured to said slide.

95

9. In a device of the character described, an elongated slide having protuberance on one side, a groove in each side of said protuberance, a hinge secured to said slide at one side thereof and an arm secured to the 100 other side.

105

10. The combination with a window frame, of a slideway secured thereto, a rib extending inwardly from each side of said slideway at the top thereof, of an elongated 110 slide having transversely flexible protuberance on one side adapted to move in said slideway, a groove at each side of said protuberance adapted to receive said ribs, a hinge secured to said slide at one side, a frame secured to said hinge, and an arm on the other side of the slide to flex the said protuberance.

115

In testimony whereof I affix my signature.
CHARLES F. GESCHICKTER.
